SHOE WELT, SEAM, AND RIB IRONING
MACHINEJames P. Fredericksen, Braintree, Mass., assignor
to United Shoe Machinery Corporation, Flem-
ington, N. J., a corporation of New Jersey

Application October 26, 1948, Serial No. 56,539

9 Claims. (Cl. 12—67.2)

1

This invention relates to a machine for operating upon shoes, and it particularly pertains to a mechanism adapted for ironing and smoothing the edges of the inseam materials and for flattening the welts of lasted welt shoes preparatory to attaching the outsoles.

In the manufacture of welt shoes, the welt and upper are stitched to the inseam rib which is then trimmed above the stitch line and as close thereto as practicable. It will be found that, at this stage of construction, the welt, instead of lying flat in the plane of the shoe bottom, will tend to curl or warp, especially in zones of high curvature such as around toe portions. In addition, it may be found that the inseam materials are irregularly trimmed so that the inseam and the welt will not uniformly contact with an outer sole when placed thereon. In order to assure a uniform contiguity of the outsole with the inseam and welt, it has heretofore been customary to pound down the inseam materials and to pound down or stretch out the welt to form a substantially flat shoe bottom to which the outer sole can be attached. This operation has usually been performed by means of rolls or hammers which beat upon the inseam materials to reduce them to a common level, and beat or otherwise flatten the welt to conform it to the plane of the shoe bottom. It has also been the common practice to slash the welt around the sharply curved toe portions so that the welt may be made to lie flat.

Machines heretofore employed to perform the above operations of leveling and flattening required numerous operating instrumentalities which not only added greatly to their cost of production but also rendered them more difficult to maintain in operation. An object of the present invention is to provide a machine which will accomplish the desired flattening of the inseam and welt by means of a single operating instrumentality, and which will be economical to manufacture and maintain.

An important advantageous feature of the present invention is that the customary pounding action and the welt slashing have been avoided by utilizing a tool having a rapid reciprocal rubbing action which smooths down the high spots, and flattens and stretches the welt, without detrimentally affecting the firmness or strength of the inseam material or of the welt.

To this end, and as illustrated, there is provided a work support having a rotatable roll adapted to enter the welt crease of a shoe being operated upon. Slightly to one side, and above

2

5 this roll, is a rubbing and ironing tool which is dependently affixed to a reciprocating head which rapidly vibrates the tool so that its rubbing surface moves back and forth along the inseam and welt in a substantially horizontal plane thus producing a burnishing action upon the work materials. By providing the work support with a vertically yieldable spring, the desired pressure may be constantly maintained between the rubbing surface of the tool and the materials as they are fed along beneath the tool. Such a rubbing or ironing action compresses and drags the high spots down to a smooth uniform level, and effectively flattens, smooths and stretches the welt in zones of curvature to produce a substantially flat shoe bottom to which the outer sole can be evenly secured.

20 These and other features of the invention are disclosed in the following specification and in the accompanying drawings, and are pointed out in the claims.

In the drawings,

Fig. 1 is a perspective view of a machine embodying the invention;

25 Fig. 2 is a diagrammatical sketch of the tool reciprocating mechanism;

Fig. 3 is a side view, partially in section, illustrating a shoe in operative position, and showing details of the work support and associated mechanism; and

30 Fig. 4 is an enlarged perspective view showing by way of example one form of rubbing tool.

The mechanism shown for imparting reciprocal movement to the rubbing tool is substantially the same as that of the Edge setting machine, disclosed in United States Letters Patent No. 368,853, granted August 23, 1887, on application of Simon Ross, Jr., and, as shown diagrammatically in Fig. 2, comprises a rotary shaft 10 carrying a crank pin 12, which causes a pitman 14 to oscillate horizontally. The pitman is pivoted at 16 by a wrist pin to a vertical arm 18 which carries a rubbing tool 20 at its lower end. The arm 18 carries an arc-shaped member 22, having its center of curvature substantially at the working face of the tool 20, and this arc-shaped member engages a flat ledge 24, mounted fixedly upon the frame of the machine, being held in contact therewith by a suitable spring. The rolling of the arc 22, upon the surface 24, causes the tool 20 to move substantially horizontally instead of in the arc of a circle. All of the foregoing structure is shown in the patent above referred to and need not be further described.

With reference to Figs. 1 and 3, the arm 18, at

its lower end, is provided with a holder 26 within which is mounted a spindle for carrying two alternate tools 20 at its lower end. These tools may be operatively interchanged by means of a handle 28, as is well understood. Thus the operator on occasions may rapidly shift to another tool which may have a different type of rubbing surface that is more suitable for the particular materials to be operated upon.

Each ironing tool 20 is removably fitted to the spindle by a hollow sleeve member 30 extending upwardly from the tool and snugly fitting around either of the cylindrical pins 32, upon which it is held in position by a spring clip 34, which slidably engages within a retaining groove 36 formed on the outside of the sleeve 30. The bottoms of the tools 20 may be formed into variously shaped burnishing surfaces for ironing the welt and inseam in a path parallel to the bottom of the shoe. While this invention is not directed to the particular design of these surfaces, it has been demonstrated that a surface similar to that illustrated in Fig. 4 will produce excellent smoothing and battenning results. It will be seen that this tool has a medial groove 38 indenting its rubbing face and providing two arcuate surfaces 40, each extending transversely to the path of reciprocal movement. Such a formation increases the efficiency of the tool, because in effect it generates two bands of contacting area between the tool and the work.

The shoe is maintained operatively positioned and the welt 44 and inseam are held pressed upwards against the tool by a rotatable work support comprising a roll or disk 42 positioned beneath the tool and carried on the outer extremity of an arm 46 which extends forward from the pedestal of the machine. The welt supporting areas of the rotatable disk 42 are arranged so as to be parallel to the path generated by the reciprocating face of the tool 20. The disk 42 is formed with a concaved bevel about its periphery to provide a thin edge 48 designed to enter the welt crease of a shoe and to extend as far as possible under the welt to afford maximum support. The edge 48 serves also as an edge gage. The support 42 is rotatably fastened to its mounting by a screw 50 which passes through a thrust bearing 52 and is threaded into a plunger element 54 axially movable within the bore of a barrel 56 formed on the end of the arm 46. The disk and plunger are normally urged upward by the force of a compression spring 58, and the limit of upward travel of the plunger is adjustably determined and maintained by a nut 60 and a lock nut 61 threaded on a stem 62 extending down from the plunger through an opening in the bottom of the barrel 56. The upper nut 60 bears against the bottom of the barrel so that the support 42 may not come in contact with the vibrating tool when there is no work present beneath the rubbing faces 40. The strength of the spring 58 should be great enough to press the work up against the vibrating tool with a force sufficient to produce a well-smoothed surface along the inseam and welt, but the upward pressure should not be so strong as to produce a binding action which would materially impair the feeding of the work. In order to facilitate the insertion of the work between the tool and the work support, the upward force of the spring 58 may be overcome and the support 42 drawn down by a treadle pull rod 64 attached to the lower end of the stem 62. If desired, the machine may be equipped with a power drive for rotating the sup-

port 42 so that the disk, when operatively positioned against the welt, will function as an automatic feed for the work.

Having described my invention, what I claim as new and desire to secure by Letters Patent of the United States is:

1. A machine for operating upon shoes to flatten and smooth the welt and trimmed inseam of a lasted shoe, comprising a work support provided with an edge gage adapted to enter the welt crease and progressively support the shoe upon the grain side of the welt as the shoe is operatively fed, a rapidly reciprocating tool having a burnishing surface engageable with the edge of the inseam and the flesh side of the welt, and means for driving said tool back and forth substantially parallel to the line of feed.
2. A machine for progressively operating upon shoes to flatten and smooth the welt and trimmed inseam of a lasted shoe, comprising a work support, a reciprocating ironing tool having a burnishing surface engageable with the flesh side of the welt and the edge of the inseam, and means for driving said tool back and forth substantially parallel to the line of work feed.
3. A machine for operating upon shoes to flatten and smooth the welt and trimmed inseam of a lasted shoe, comprising a work support engageable with the grain side of the welt as the shoe is operatively fed, a reciprocating ironing tool spaced above the support, means for yieldably mounting said support for movement relative to the tool, and means for driving said tool back and forth substantially parallel to the line of feed.
4. A machine for progressively operating upon shoes to flatten and smooth the welt and trimmed inseam of a lasted shoe, comprising a reciprocating ironing tool having a burnishing surface engageable with the flesh side of the welt and the edge of the inseam, a rotatable work supporting roll spaced beneath said tool, and means for driving the tool back and forth substantially parallel to the line of work feed.
5. A machine for progressively operating upon shoes to flatten and smooth the welt and trimmed inseam of a lasted shoe, comprising a reciprocating ironing tool, a rotatable work supporting roll spaced beneath said tool, means for yieldably urging the roll upwards towards said tool, and means for driving the tool back and forth substantially parallel to the line of work feed.
6. A machine for operating upon shoes to flatten and smooth the welt and trimmed inseam of a lasted shoe, comprising a work support engageable with the grain side of the welt as the shoe is operatively fed, and a vibratory tool having a burnishing surface extending substantially in the plane of the shoe bottom and engageable with the flesh side of the welt and the edge of the inseam materials.
7. A machine for progressively operating upon shoes to flatten and smooth the welt and trimmed inseam of a lasted shoe, comprising a reciprocating ironing tool, a rotatable work supporting roll spaced beneath said tool, yieldable pressure means for normally maintaining said tool and roll in operative contact with the work, and means for driving the tool back and forth substantially parallel to the line of work feed.
8. A machine for operating upon shoes to flatten and smooth the welt and trimmed inseam of a lasted shoe, comprising a work support engageable with the grain side of the welt as the shoe is operatively fed, a vibratory tool having

a burnishing surface extending substantially in the plane of the shoe bottom and engageable with the flesh side of the welt and the edge of the inseam materials, and yieldable pressure means for normally maintaining said support and tool in operative contact with the work.

9. A machine for progressively operating upon shoes to flatten and smooth the welt and trimmed inseam of a lasted shoe, comprising a work support engageable with the grain side of the welt as the shoe is operatively fed, a reciprocating

ironing tool spaced above the support, and yieldable pressure means for effecting relative movement of the support and tool, said movement being in a direction heightwise of the shoe to vary the spaced-apart relationship of the support and tool in order to automatically accommodate for progressively varying thicknesses of the work.
